UNITED STATES PATENT OFFICE

2,435,677

ARCH SUPPORT HEEL

Arthur H. Gilman, Spokane, Wash.

Application December 8, 1945, Serial No. 633,585

3 Claims. (Cl. 36—76)

1

My invention relates to improvements in an arch support heel and has as its principal object the provision of certain improvements over the heel covered by my prior Patent No. 2,113,133 for arch support issued April 5, 1938, whereby additional advantages of the arch support are realized by the wearer.

In the arch support of my prior patent a resilient heel is provided with a forward extension, also resilient, arranged in such fashion as to extend forwardly under the arch of the foot to give the arch support at the critical time when the strain is most severe thereon. According to my present invention I provide an improved means for adjusting the arch support to enable the wearer to maintain and increase the effectiveness of the support as the arch is improved by wearing it, without the necessity of cement or special shoe repair equipment.

The nature and advantages of my invention will appear more fully from the following detailed description and the accompanying drawings wherein a specific embodiment of the invention is shown. It should be understood, however, that the drawings and description are illustrative only and should not be considered as limiting the invention except insofar as it is limited by the claims.

In the drawings:

Figure 1 is a side view of a shoe embodying the arch support of my prior patent;

Figure 2 is a fragmentary side view of the heel portion of the shoe showing my improved arch support means applied thereto;

Figure 3 is a bottom view of the shoe heel;

Figure 4 is a view like Figure 2 but illustrating a modification in the application of my improved arch support means;

Figure 5 is a plan view of a wedge employed in the improved arch support means; and

Figure 6 is a view in side elevation of the wedge.

In the application of the arch support to which my invention applies a heel 10 of natural or synthetic rubber is provided with a forwardly extending narrowed portion 11 as an integral part thereof. This portion projects under the mid-portion of the arch of the foot. It is as thick as the heel itself and serves to lift the arch as weight is placed on the foot to give a resilient support at the arch. I have found that upon wearing this arch supporting means the arch generally improves so as to cause the wearer to lose, in part, the advantages provided. Also the extended portion 11 tends to flatten and lose part of its resiliency and to wear thinner

2

in use, thus making it less effective. In my prior patent this difficulty was remedied by the insertion of lifts or pads which were secured by cement to the shank of the shoe. To correct the arch further the lift was unfastened from the shank and an addition lift placed over it. This manner of building up the arch support could not readily be taken care of by the wearer and as a result the full advantages were lost due to inconvenience or inability of the wearer in getting the lifts changed.

In order to cure the difficulties enumerated above, I provide means to restore the extended arch supporting portion. One form of applying such means is illustrated in Figure 2 of the drawings. It will be noted by comparing Figures 1 and 2 that the portion 11 when first applied was curved downwardly toward its free end as indicated at 12, by the pressure exerted against the shoe shank. The tension will eventually give a certain set to the rubber and thus weaken the support. In addition, the protruding lower edge 13 of the portion 11 tends to wear off in use as shown at 14 (Figures 2 and 4) to reduce the effective depth of the arch support. The means employed to restore the effectiveness of the arch support comprises a tapered wedge member 15 of yielding material such as natural or synthetic rubber, or leather. This wedge member 15 as shown in Figures 5 and 6 is widened out at its thinner edge to conform to the shape of the portion 11.

According to the showing in Figure 2 of the drawings the wedge member is inserted between the shoe sole 16 and the top surface of the portion 11. It bends the portion 11 down and thus overcomes the loss of effectiveness due to the "set" given the portion 11 by holding it bent as shown in Figure 1. Also the front end of the portion 11 is again lowered to extend below the heel level so as to give the arch support at the critical time when the heel comes off the ground. The wedge member 15 is provided with two spaced apertures 17 to receive securing members such as short pins 18 shown dotted in Figure 2. These pins are set in recesses 19 provided in the forwardly extended portion 11.

Figure 4 of the drawings illustrates another way of applying the wedge member 15. In some cases the extension 11 may be difficult to separate from the shoe sole and in that case it is split at a level close to the shoe sole and the member 15 is inserted as shown. The pins 18 are used to secure the member 15 in place. The pins may

be made of any suitable material such as metal or rubber.

As the arch improves and as the extension 11 wears further, thicker wedges 15 may be applied. The wedges may be made up in sets of different taper so that the effectiveness of the portion 11 in supporting the arch may be repeatedly restored.

The application of the tapered wedges 15 is accomplished by bending the portion 11, as shown in Figure 2, or the lower part of portion 11, as shown in Figure 4, back far enough to insert the pins 18 in the recesses 19. Then the wedge is forced inward until the pins engage in the openings 17. The resiliency of the rubber is sufficient to permit this manner of assembly with no difficulty.

Having thus described my invention, I claim:

1. In a shoe, the combination with a heel and means for fastening it to the shoe, and a narrowed resilient portion projecting from the front of the heel under the shank of the shoe and providing support directly for the shank of the shoe, of a wedge member inserted beneath the shoe shank and removably mounted by said resilient forwardly projecting portion, said portion having spaced pin recesses therein and pins seated in said recesses, the wedge member having apertures receiving said pins.

2. In a shoe, the combination with a heel and means for fastening it to the shoe, and a narrowed resilient portion projecting from the front of the heel under the shank of the shoe and providing support directly for the shank of the shoe, of a wedge member inserted beneath the shoe

shank and removably mounted on said resilient portion, the said portion having pin receiving recesses in the top surface, removable pins seated in the recesses and projecting above the top surface thereof, and said wedge member having apertures receiving the projecting portions of the pins.

3. In a shoe, the combination with a heel and means for fastening it to the shoe, and a narrowed resilient portion projecting from the front of the heel under the shank of the shoe and providing support directly for the shank of the shoe, of a wedge member inserted beneath the shoe shank and removably mounted between upper and lower sections of said resilient forwardly projecting portion, said portion having spaced pin recesses therein and pins seated in said recesses, the wedge member having apertures receiving said pins.

20 ARTHUR H. GILMAN.
